UNITED STATES PATENT OFFICE.

ALMON B. GLOVER, OF BIRMINGHAM, CONNECTICUT, ASSIGNOR, BY MESNE ASSIGNMENTS, TO THE EASTERN PAPER BAG COMPANY.

PAPER-BAG MACHINE.

SPECIFICATION forming part of Reissued Letters Patent No. 9,428, dated October 19, 1880.
Original No. 200,654, dated February 26, 1878. Application for reissue filed July 23, 1880.

To all whom it may concern:

Be it known that I, ALMON B. GLOVER, of Birmingham, in the county of New Haven and State of Connecticut, have invented certain new and useful Improvements in Machines for Making Paper Bags; and I do hereby declare that the following is a full, clear, and exact description of the invention, which will enable others skilled in the art to which it applies to make and use the same, reference being had to the accompanying drawings, and to the letters of reference marked thereon, which form a part of this specification.

This my invention has for its object the production of a machine for the manufacture of that class of paper bags having satchel bottoms.

In this class of machines it has been common, before this my invention, to form the diamond fold by means of a finger, over which the open end of the tube has been moved, as in the Knight patent, No. 116,842; and so, also, a rotating drum provided with a jaw has been made to grasp one ply of a tubular paper blank at one end and to carry it forward to a finger, over which the open end of the tubular blank, one ply of which is so held by this jaw, is drawn until the finger extended within the blank from the outside and acting against the inner ply thereof lays back one ply of the blank and forms the diamond fold.

In this my invention the web of paper is fashioned into a tube about a former having extended in front of it a follower or inner plate, which is retained within and supports the tube near its open leading end during the formation of the diamond fold, said follower, besides keeping the upper and lower plies of the tube separate, also acting to hold one ply in proper horizontal position, while the other ply is seized or grasped by a circularly-moving ply-gripping device and carried backward in a direction opposite the direction of movement of the tube, when acted upon by the tube-feeding mechanism, such backward movement of the ply-gripping device with one ply of the tube grasped thereby, while the other ply is held by the follower or inner plate within it, laying or forming the usual diamond fold. As the 50 ply-gripping device carries back one ply, as de-

scribed, the center or transverse fold for the diamond fold is defined by means of a crimping-plate that is extended across the tube, it bearing upon the ply, being lifted by the ply-gripping device. The diamond fold having been formed, holding-plates, such as used in the Knight patent, are moved forward from each side of the tube over and down upon the central part of the diamond fold, holding it in place, while the first and second cross or final folding blades, acting against the under sides of the front and rear corners of the diamond fold, are made to approach the center line or central crease of the diamond fold, sweeping the said corners one toward the other, forming the two cross or final folds, that, properly pasted, complete the satchel bottom. The bottom finished, the tube is fed forward for the proper distance and cut off, and its free or leading end is again opened and acted upon, as just described.

To insure in a positive manner that that ply of the tube to be seized by the ply-gripping device shall be placed in exactly the proper position to be grasped by the ply-gripping device, I have provided at the front end of the inner plate, within the tube, an opening device or finger that is acted upon at the proper time and turned just far enough to insure the separation of the two plies and hold the ply resting upon it in position to be easily and surely grasped by the ply-gripping device. This finger or lifter enables the machine to operate with certainty.

Figure 1 is a plan view of a machine embodying my invention, the parts being in the position they will occupy just after the ply-gripping device has laid back one ply of the tube in the formation of the diamond fold, the bag not being, however, shown; Fig. 2, a longitudinal horizontal section on the line 2^x 2^x, Fig. 3; Fig. 3, an elevation of the delivery end of the machine; Fig. 4, a vertical longitudinal section through line 4^x 4^x of Fig. 1; Fig. 5, a sectional detail on the line 5^x 5^x of Fig. 6; Fig. 6, a plan view of the ply-gripping device below the dotted line 6^x 6^x of Fig. 5; Fig. 7, a sectional detail of the side folder drawn back; Figs. 8 and 9, details showing the follower or device located within the tube as the diamond 100

fold is being made by the ply-gripping device, which engages one ply of the tube and lays or draws it back; and Figs. 10, 11, 12, and 13 are diagrams of the devices for automatically folding and finishing the bag-bottom, the said figures showing, in succession, the operations necessary for that purpose.

The frame-work A' is of proper shape to support the working parts.

10 A A represent the outside, and A² the central part, of the skeleton tube-former, about which the web of paper is folded as it is drawn automatically into the machine from the roll after one edge of the paper has been properly supplied with paste in any usual way.

15 In practice the portions A A will extend backward nearly to the tube-pasting devices; but in the drawings they are shown broken off near the receiving end of the machine.

20 The central part, A², of the tube-former is connected with the side pieces, A A, by cross-pieces, as at C. (See Fig. 1.) The skeleton tube-former is supported from the frame or arch A' by the hanger a', so that one edge of 25 the paper may pass over and the other under the lower part of the hanger.

25 The outside pieces, A A, of the former may in practice be expanded or contracted in width, or, rather, be adjusted laterally with relation 30 to each other, or may be changed for others to accommodate for the manufacture of bags of different width.

35 Above the flattened central portion, A², of the former is placed the hollow steam-box D or drier, to set or dry the pasted seam in the tube supported centrally over the part A². This steam-drier D is connected with a lever, D', operated by a cam, 1, on the cam-shaft X, so as to raise the drier just before the paper 40 tube is fed forward and lower it as soon as the tube comes to rest, it thus operating to partially dry or set by heat the pasted seam of the tube. The box may have a steam-inlet at o and an exit at n for steam and water of 45 condensation.

45 The intermittently-acting paper-feeding rollers B B, which serve to draw the web of paper from the roll about the skeleton-former into the machine to form the tube and feed it and 50 the bag out of the machine, are grooved centrally to permit the passage between them of the shank e⁶ of the inside plate, E, or follower, which at all times during the formation of the diamond fold remains within and holds down 55 one ply of the tube while the other ply is grasped and laid or carried backward. This shank e⁶ reciprocates in bearings formed for it in the central portion, A², of the former. The inside plate, E, is shown as somewhat of triangular 60 form, its two forward edges being equally but reversely inclined from the end of the plate backward, (see Fig. 9,) its inclined edges acting to accurately define the diagonal folds of the leading half of the diamond fold.

65 The finger e', located at the front end of the plate E, is so operated as that it positively

insures the correct presentation or positioning of that ply of the tube to be engaged by the ply-gripping device U.

The shank e⁶ derives its reciprocations at 70 the proper times from the arm or lever F on the shaft g³, a short arm, g², of the said shaft being connected by link g' with a lever, G, actuated by the cam 2 on shaft X.

The finger e' is pivoted upon the plate E, 75 and just as the diamond fold is to be made by turning back one ply of the tube it is lifted above the plate E, (see Fig. 8, this figure being exaggerated in this particular,) so as to separate one from the other ply of the tube (shown 80 in dotted lines) by means of a lifting-rod, e², guided in suitable brackets and connected at its lower end with the lever e³, actuated at the proper time by the cam 5.

The finger e' is notched opposite where the 85 ply-gripping device is to grasp one ply of the tube, to thus prevent the ply-gripping device from seizing the finger as it is closed upon one ply of the tube preparatory to being moved in a semicircular path.

90 The rest plate or table H is supported by the guided and vertically-movable rods h, connected at their lower ends with the cross-bar k, attached to the rod L, raised at the proper times by the lever M, actuated by the cam 5. 95 The crimping-plate N, extended across the machine and forward partially across or substantially to the center of the table H, is supported on guided rods n', connected loosely at their lower ends with levers J, pivoted centrally at r, the said levers being at their other ends connected with the rods h, thus insuring 100 for the table and crimping-plate simultaneous movements in opposite directions.

R R are side holders or guides, the width of 105 which determines the width of the bottom of the bag. They may be made of any desired width adapted to the size of the bag, and may be removed and exchanged, as need be, for others of any required size. They are attached 110 to arms or levers r', (see Figs. 5 and 7,) which are severally connected to the slides r², a spring, r³, serving to bear down upon the rear end of each of the levers r', and to normally throw upward the holders R R when they are 115 not otherwise forced downward. The slides r² are each connected with an angle-lever, r⁴, and these levers at their lower and inner ends are jointed to a vertical rod, r⁵, which connects with a lever, r⁶, deriving its motion from cam 120 4. The movements of the side folders inward and outward are coincident and simultaneous. As the slides r² within the hollow arms r⁷ are moved forward by the said levers r⁴ the rear ends of the holder-carrying levers r' strike the 125 adjustable holder-depressing devices, (shown as screws r⁸,) which so turn the levers r' as to force downward the holders R R, pressing the tube upon the crimping plate and table.

130 The first cross folder or blade, O, for forming the cross-fold at the rear of the diamond fold, is reciprocated forward and backward over the

holders R by the rock-shaft o⁴, cranks or arms thereon, pitman o², lever o', and cam 6, a spring, o⁵, moving the lever o' in the opposite direction.

The second cross-folder or blade, P, is moved 5 upward and forward and backward and downward by the rock-shaft p⁵, cranks p⁴, rod or pitman p³, lever p', and cam 6, the spring p² moving the lever p' in a direction opposite that of the said cam.

10 The ply-gripping device U, to catch and carry back one ply of the tube, while the other ply is held down and separated from it by the follower or inner plate, and form or lay the diamond fold, is shown as composed of two jaws, a^x b^x, having lips c², the jaws being pivoted upon an arm, u², of a tubular hub, u', which arm is fulcrumed at u⁶. A dog, u¹, made as an elbow-lever, pivoted at u⁷ in arm u², is acted upon by the wedge s³ attached to the collar s² 15 as the collar is moved forward, and the dog so turned on its pivot moves the rod u⁵ longitudinally, causing its wedge-shaped end (see Fig. 6) to act upon and close the jaws a^x b^x of the ply-gripping device upon one ply of the tube. 20 25 the hub u' just before this having been turned or rotated sufficiently far to place the lugs c² of the ply-gripping device in the position shown in Fig. 10, at which time the parts are as in Fig. 8, in which latter figure the dotted lines 30 denote the tube, upon one ply of which the ply-gripping device is to be closed, as in Fig. 10, preparatory to partially revolving the hub and carrying the ply-gripping device to the 35 position shown in Fig. 11, which figure shows one ply of the tube drawn back and the diamond fold laid.

The ply-gripping device receives a circular movement of about one hundred and eighty degrees over the arc represented by the curved 40 dotted lines, Figs. 4 and 8, by means of the lever S, (see Fig. 4,) link S', and toothed segment V, which is made to engage the pinion 10 on the hub u'.

The collar s², carrying the wedge s³, is moved 45 forward and backward at the proper times by the lever S', Figs. 1 and 2, actuated by the cam 1, the forked upper end of the said lever entering an annular groove made in the said collar, as shown in the drawings. A suitable 50 spring operates to move the dog u¹ and rod u⁵ backward when the wedge s³ and collar s² are moved backward.

The finger e', attached to the plate E, so as 55 normally to remain down substantially at the level of the said plate, is designed to open the end of the paper tube to aid the ply-gripping device in taking hold of one ply of it, as in Figs. 8 and 10, the finger at that time being positively lifted, as before described. This 60 finger e', between its ends, has a downward bend or depression, 14, that enters the opening made through the plate E. The lifting-rod e² acts against one ply of the paper opposite this depression 14 and opening in the 65 plate E, and thus obviates breaking that ply of the paper as the finger is lifted.

T is a paster-brush for pasting the bottom of the bag. It is operated by a lever, t', which is connected by a link, t², with a cam-lever t³, which is actuated by the cam 3. 70 The upper end of t' is pivoted to a slide, t⁴, which carries this paster-brush T. This slide, by means of guides which run in irregular slots in a vertical plate, t⁵, secured to a bracket, t⁶, gives to the brush its proper movement to receive its paste from the pasting-roller t⁷ in the paste-cup t⁸, and also downward and other movements to deliver its paste to the proper part of the folded bottom of the bag, and then to withdraw therefrom and return to its original position, ready for the next pasting action. The place on the bottom of the bag at which it deposits the paste is distinctly shown at Fig. 11.

W is a pad, which is brought down upon the 85 folded bottom to cause the folded parts to adhere more closely together after the bottom is fully folded and before the folders commence to recede. It is then raised a little, and acts as a guide to keep the folds from rising, so as to 90 permit their passage through the shears, hereinafter mentioned, when the bag is fed forward by the feed-rolls. This pad is operated at the proper periods through the agency of its arm W', rock-shaft w', crank w², and cam-lever w³, 95 which latter is actuated by a cam-projection on the driving or hand wheel 7, a coiled spring, w⁴, on the shaft w' serving to return the pad to its normal position.

c c' are the shears for cutting off from the 100 tube the finished bag, one of the blades of these shears being preferably stationary.

The feed-rollers B are driven by appropriate gears b' b² and a pawl or clutch, b³, connected to a yoke-bar, b⁴, which is actuated from 105 the main shaft.

In the operation of the machine it will be supposed that the flattened tube enveloping the former has been drawn forward by the feed-rolls B and passed under the crimping-plate 110 N and over the table H until the leading end of the tube reaches the shears c c', which cut off the tube transversely, the plate E at that time being nearly up to the shears. Just as the tube is to be cut off the feed stops and the 115 table H is made to rise and the crimping-plate to drop and grasp the tube between them.

I will now describe the operation of forming 120 a bag from that portion of the tube between the shears and the feed-rollers. This portion of the tube, as it has been stated, is held clamped between the crimping-plate and table, with the point of the inner plate, E, nearly up to the shears. As the upper shear-blade descends the 125 ply-gripping device U is turned down, following closely after the shears, until the ply-gripping device is brought into nearly a horizontal position, it being thus brought into position to engage one ply of the end of the tube formed by the shears at that descent. The 130 shears having cut the tube, the finger e' is lifted by the rod e², opening the end of the tube,

as in Fig. 8, when the ply-gripping device takes hold of the raised ply of the paper-tube opposite the notched end of the finger grasping the said ply, as in Figs. 8 and 10. The ply-gripping device is then rotated backward, carrying with it the ply of paper grasped by it, while the other or lower ply is held down by the follower, laying backward upon the tube that ply of it held by the ply-gripping device, forming the diamond fold represented in Fig. 11, the diagonal forward end of the plate E defining the diagonal folds of the diamond fold. As the ply-gripping device is moved to carry backward that ply grasped by it, as in Fig. 10, it bends that ply over the crimping-plate N, extended transversely across the tube, as in Fig. 10, the crimping-plate defining the usual central crease or fold for the diamond fold or bag-bottom. As the ply-gripping device reaches its backward position and completes the diamond fold the holders R R are moved forward, as in Fig. 11, over the diamond fold and lowered upon and so as to hold it upon the crimping-plate and table. During the time that the holders are so moved the paster, operated as described, is caused to apply paste to the diamond fold, as shown by the dotted lines, Fig. 11, the paster in practice sliding a short distance forward and backward in contact with the paper to brush on the paste and make better work than could be done by simply printing it on, as by pressing the paster upon and then lifting it from the paper. After the ply-gripping device, in its downward movement, has partially folded across the crimping-plate the ply of the tube held by it, and before the ply-gripping device or the holders R R have arrived at the positions denoted in Fig. 11, the table H is lowered a little and the crimping-plate correspondingly raised to release their hold upon the tube and the follower within it sufficiently to permit the follower and inner plate, E, to be, by a quick movement, withdrawn backward behind the front edge of the crimping-plate, when the table H and crimping-plate are again quickly brought together to clamp the paper between them, and it is after this that the ply-gripping device and holders complete their movement indicated in Fig. 11, and the ply-gripping device is then released from the ply held by it and started forward.

The paster is moved back out of the way of the first cross-folder or blade, O, which latter is then thrown forward in the direction of the movement of the tube from the position Fig. 11 to the position Fig. 12, sweeping the rear-most corner of the diamond fold, laid and held substantially parallel with the tube, forward over the holders R, forming in the diamond fold the first cross-fold. Then the second folder or blade, P, is thrown upward and forward from the position Fig. 12 to that shown in Fig. 13, sweeping the leading corner of the diamond fold back over the holders, as in the said Fig. 13, forming the second cross or

final fold, lapping the pasted leading corner of the diamond fold over upon the opposite corner previously folded over and yet held by the first folder, O. The point-pressing pad W is then caused to descend upon the corners previously lapped over by the folders O P and press the said corners and parts of the bag-bottom closely together, causing the pasted parts of the paper to adhere and complete the bag-bottom. This done, the side-folders commence to withdraw, but the cross-folders O P keep their position until the holders are so far withdrawn as to be no longer in contact with the parts of the paper folded over or about them, when the cross-folders O P are drawn back and returned to their first or normal positions and the pad rises. This timing of the movement of the holders and cross-folders, moving the holders back first, prevents the unfolding or drawing back of those parts of the bag-bottom folded over upon the holders by the cross-folders. Should the cross-folders be withdrawn first, their pressure and friction on the folded corners of the diamond fold between them and the holders would more or less pull back the said lapped corners. After this the table and crimping-plate are separated to release the tube, leaving the completed bottom and more or less of the tube, according to the length of the bag to be formed, to be fed forward between the open blades of the shears, which at the proper time act to cut off the tube, completing the bag. While the feed is moving the tube forward in this way the pad W is raised but little above the bag-bottom and the follower is thrust forward, the two co-operating together to insure the correct entrance of the bag-bottom and its tubular connected parts between the shears, and after this the pad is completely raised, and the end of the tube is again in readiness to be operated upon, as already described, to form the bottom for another bag.

Prior to my invention it had been customary to pinch a tube, cause vertically-placed side plates to move forward, meet the side edges of the projecting free end of the tube or tubular blank, and form a diamond fold by pressure against the tube from its folded side edges inward, and after this vertically-movable plates have acted upon the corners of the diamond fold, projecting above and below the body of the tube at right angles, and have laid such corners over the side-folders, and after this the bag-bottom has been partially turned over to bring the completed bottom next to and in contact with the main part or body of the tube for packing.

The rolls may be adjusted to feed any desired length. While they are feeding forward and outward one of the finished bags, and also drawing along the paper tubing for another, the former-plate is coming forward at the same time to its position to form the bottom of the next bag.

In this my apparatus it will be noticed that

the ply-gripping device engages one ply of the tube just as the tube is severed, and carries one ply directly backward, while the other ply of the tube is supported or guided internally quite to the extreme end of the tube, and that I form the bag-bottom at the end of the long tube before I sever the bag-length from the tube.

I do not claim a follower provided at its front end with two springs the normal tendencies of which are to remain separated, and which, when permitted to open, co-operate with rollers to form at the end of the tube a diamond fold.

15. I claim—

1. In a paper-bag-making machine, a follower or inner plate located within the tube at its leading end, combined with a circularly-moving ply-gripping device to grasp and carry backward one ply of the tube, while the other ply is held from following it by the follower or plate within it, substantially as described.

2. In a paper-bag-making machine, a follower or inner plate located within the tube at or near its leading end, and a circularly-moving ply-gripping device to grasp and carry backward one ply of the tube, combined with the crimping-plate extended transversely across the ply, being laid back by the ply-gripping device to define the central or transverse crease for the diamond fold, substantially as described.

3. In a paper-bag-making machine, the inner plate, E, located within the tube, and having the oppositely-inclined or diagonal edges, combined with means to lay back one ply of the said tube in the formation of the diamond fold, the diagonal edges of the said plate defining the diagonal folds in the leading end of the diamond fold, substantially as shown and described.

4. In a paper-bag-making machine, the finger and support for it within the tube at its leading end, combined with means to act upon and lift the finger to lift or separate one from the other ply of the tube, substantially as described.

5. The combination, in a paper-bag-making machine, of the finger located within the tube, its support, also located within the tube, means to lift the finger to separate one ply of the tube from the other, and ply-gripping device to engage one ply of the tube and carry or lay it back upon itself, while the other ply is held internally and prevented from following the ply-gripping device, substantially as described.

6. The combination, in a paper-bag-making machine, of the former located within the tube, the crimping-plate extended transversely across the tube, and circularly-moving ply-gripping device to grasp one ply of the tubular piece of paper and positively carry it backward upon itself, substantially as set forth.

7. In a paper-bag-making machine, the table and crimping-plate and means to operate them simultaneously in opposite directions to clamp

and release the tube, combined with the feeding mechanism for the tube and the follower and the ply-gripping device to grasp one ply of the tube and carry it back, substantially as shown and described.

8. In combination, the rocker arm F, the skeleton-tube former A², suspended and supported as described, the reciprocating shank or shover e⁶, and the plate E, and the recessed or grooved rollers B B, substantially as and for the purposes described.

9. The triangular former E, provided with a notch at its tip or point and with an opening, e⁴, through its body, as and for the purposes set forth.

10. The combination of the vertically-reciprocating crimping-plate N and the similarly-actuated table H, operating by separating to permit the withdrawal of the follower, and by closing together to clamp the tube between them to make the bottom of the bag, substantially as described.

11. The combination, with the follower, of the finger e⁴, loosely attached thereto, and a lifting device operating to elevate said finger, the construction permitting the finger, when released by the lifter, to freely drop to place by its own gravity, for the purposes described.

12. The ply-gripping device U, combined with the arm u², hub u¹, rod u³, dog u⁴, sliding collar s², and wedges s³, substantially as and for the purpose set forth.

13. The side holders, R R, having a horizontally-reciprocating motion, and vertically raised and depressed to act upon the tubes while passing through the forming devices, as described, in combination with the movable table H and plate N, actuated to approach toward and separate from one another, and the folders O P, similarly operated, substantially as specified.

14. The side holders or guides, R R, in combination with levers r¹, springs r², slides r³, and levers r⁴, substantially as shown and described.

15. In combination with the stationary paste-cup t⁸ and its pasting-roller t⁷, the paste-brush T, having the movements, substantially as described, derived from the slide t⁴, slotted plate t³, link t², and lever t¹, as shown and set forth.

16. In combination, the former A A A², the steam-box D, its operating-lever D', and cam to move it, substantially as shown and described.

17. The feed-rollers B B, grooved as described, in combination with the skeleton-frame A A² and with the bar or arm e⁶ of the plate E, the combination permitting this bar to operate the said plate at the same time that the feed-rollers are feeding the paper.

18. In combination, the tube-former A A A², the intermittently-acting steam-box, grooved feed-rollers B B, and the described devices for forming the bottom of the bag.

19. In combination, the tube-former A A A²,

steam-box D, grooved rollers B B, bottom-forming devices, and the pressure-pad W, the combination operating as set forth.

20. In combination, the tube-former A A A², steam-box D, grooved rollers B B, bottom-forming devices, pressure-pad W, and the paster T, the combination operating as set forth.

21. In combination, the tube-former A A A²,

steam-box D, grooved rollers B B, bottom-forming devices, pressure-pad W, paster T, and the shears c c', the combination operating as set forth.

ALMON B. GLOVER.
